[57] CLAIM

The ornamental design for a chair, as shown and described.

DESCRIPTION

FIG. 1 is a perspective view showing my new design;
FIG. 2 is a side elevational view taken from the left side of
FIG. 1, the opposite side of the chair being a mirror image
of the view shown in FIG. 2;

FIG. 3 is a front elevational view.

FIG. 4 is a back elevational view; and,

FIG. 5 is a top view of the design.

The fragmented depiction of the line or wrapped legs and
arm rest members is understood to be continuous.

The fragmented depiction of a weave pattern shown on the
body of the chair is understood to repeat uniformly through-
out the circumscribed area.
